UNITED STATES PATENT OFFICE.

JOHN C. DUEBER, OF CANTON, OHIO.

DESIGN FOR A WATCH-CASE.

SPECIFICATION forming part of Design No. 21,346, dated February 16, 1892.

Application filed December 16, 1891. Serial No. 415,323. Term of patent 14 years.

To all whom it may concern:

Be it known that I, JOHN C. DUEBER, a citizen of the United States, and a resident of Canton, county of Stark, State of Ohio, have 5 invented a new and useful Design for Watch-Cases, of which the following is a full, clear, and exact description, reference being had to the accompanying drawings, making part of this specification.

10 My invention relates to a new and useful design for watch-cases, the leading feature of which is the peculiar form or design of the bezel or ring portion of the lid and the rim of the case.

15 Figure 1 of the accompanying drawings is a view in perspective of a watch-case, showing the design; and Fig. 2 a side elevation.

The central portion of the lid A may be of any of the well-known forms and ornamentation, or a crystal may be secured in the bezel-ring B in the usual way. The rim C of 20 the case, as shown, is a plain oval polished ring, to the sides of which are secured in the

usual way the front and back lids, the edge or bezel portion of which is ornamented by a 25 series of grooves a, extending across the face of the bezel portion of the lid on lines converging to a point above the center of the lid A, thus forming a series of oval ribs D, arranged side by side across the face of the 30 bezel B.

The leading feature of the design consists of the plain oval rim and lids, having the edge or bezel portion thereof ornamented with a series of oval ribs, as shown.

35 What I claim as new, and desire to secure by Letters Patent, is—

The design for watch-cases, herein shown and described.

In testimony whereof I have hereunto set 40 my hand this 30th day of November, A. D. 1891.

JOHN C. DUEBER.
